BOTTLE

George L. Green, 1307 Ewing St., Kansas City, Mo., and Melvin O. Nelson, 16004 R. D. Mize Road, Independence, Mo.

Filed Apr. 22, 1963, Ser. No. 74,541

Term of patent 14 years

(Cl. D58—25)

FIG. 1

The dominant features of our design reside in the portions shown in full lines.

We claim:

The ornamental design for a bottle, as shown and described.
